UNITED STATES PATENT OFFICE.

BERTRAND S. SUMMERS, OF CHICAGO, ILLINOIS.

DIGESTER FOR CHEMICAL TREATMENT OF SUBSTANCES.

SPECIFICATION forming part of Letters Patent No. 670,485, dated March 26, 1901.

Application filed July 28, 1898. Serial No. 687,110. (No model.)

To all whom it may concern:

Be it known that I, BERTRAND S. SUMMERS, a citizen of the United States, residing at Chicago, in the county of Cook and State of Illinois, have invented a certain new and useful Improvement in Digesters for Chemical Treatment of Substances, of which the following is a full, clear, concise, and exact description, reference being had to the accompanying drawings, forming a part of this specification.

My invention relates to a digester for the chemical treatment of substances, my objects being to provide means whereby a solution may be readily transferred from one digester or vat to another, and, furthermore, to provide means whereby materials or substances in a digester may be successively subjected to several different solutions or chemicals without removal from the digester.

In accordance with my invention in the preferred form thereof two digesters are employed connected by a system of piping, whereby the solution may be passed from one digester to the other by creating a difference of gaseous pressure between the two digesters, the piping also accommodating the passage of two different liquids to and from the digesters. In order to effect the transfer of the liquid from one digester to the other by gaseous pressure, it is necessary to provide means whereby a maintained difference of pressure may be employed, to thus effect the passage of all of the liquid in one digester to the other digester. I preferably provide a heater in connection with each of the digesters, the heater in practice taking the form of a steam-coil provided in the interior of each digester, to thus produce an excessive pressure which serves to force the liquid from one digester into the other digester, the coils being connected with a steam-supply pipe, whereby steam may be admitted to either coil, to thereby convert the liquid in the digester into steam. I also provide a vacuum-pipe, whereby a vacuum may be produced within one of the digesters, to thus create a difference of gaseous pressure which forces the liquid from one digester into the other.

I have illustrated my invention in the accompanying drawings, in which—

Figure 1 is a view of the digesters in ele-

vation, partially in section. Fig. 2 is a plan view thereof.

Like letters refer to like parts in both figures.

The digesters *a* *b* are provided with covers *a'* *b'*, respectively, which can be removed for the insertion of the material to be treated and which are capable of being locked in position to withstand pressure within the digester. Upon the respective covers are provided the pressure-gages *a⁵* *b⁵*, thermometers *a⁸* *b⁸*, and the valves *a⁶* *b⁶*. Within the digester *a* is a coil of steam-pipes *a²*, connected by pipe *a³* with a boiler or other steam-supply, while a coil of steam-pipes *b²* is provided within the digester *b* and connected with the steam-supply by a pipe *b³*. In the pipes *a³* and *b³* are the valves *a⁷* *b⁷*. The coils *a²* and *b²* are connected with an exhaust by means of pipes *a⁴* *b⁴*, respectively. A pipe *c* extends between and connects the lower ends of the digesters and has two valves *c'* *c²* on opposite sides of a pipe *d* connected therewith and having connected thereto a pipe *d'*, extending to a water tank or supply, and a pipe *d²*, extending to an exhaust, valves *d³* *d⁴* being provided in the respective pipes. A pipe *e* extends from the pipe *c* and is connected with a pipe *e'*, extending to the steam-supply, and with a pipe *e²*, extending to a vacuum pump or ejector, valves *e³* *e⁴* being provided in the respective pipes.

The apparatus as above described, although applicable for various purposes, is particularly designed for the treatment of paper-pulp, fibers, such as flax, and the like to permit the same chemical solution to operate successively upon substances in the two digesters and, furthermore, to permit the access of a second liquid or solution to each digester after the first solution is passed therefrom. The solution being in the digester *a* and the pulp or other material being immersed therein and the cover *a'* secured in position, steam is passed through the coils *a²* to heat the solution to the proper temperature. At the completion of the operation when it is desired to transfer the solution to the other digester the valves *c²* and *e⁴* are opened, whereby a vacuum is created within the digester *b*, and the valve *e²* is then closed and the valve *c'*

opened, whereby the digester *b* is placed in communication with the digester *a*. The pressure within the digester *a* and the vacuum within the digester *b* create a difference of 5 pressure which effects the transfer of the solution from the digester *a* to the digester *b*. To assist the vacuum in effecting the transfer, the steam-pressure in the digester from which the liquid is removed may be employed, or 10 the digester from which the liquid is being removed may be connected with the atmosphere by opening, for instance, the valve *a*⁶, in which case the pressure of the atmosphere will assist the vacuum in effecting the transfer. After the transfer the valves *c'* and *c*² 15 are closed and steam is passed through the coils *b*² to heat the solution to the proper degree. In order to subject the paper-pulp or other material in the digester *a* to the second 20 liquid or solution, the valves *c'*, *a*⁶, and *d*³ are opened and the liquid from a tank or other source of supply is admitted to the digester *a*, or where the liquid desired is water the valves *e*³ and *c'* may be opened to admit steam 25 to the interior of the digester, the steam being condensed therein by the admission of water through the valve *a*⁶ or otherwise to produce the liquid. After the liquid has been 30 conveyed to the digester *a* steam may be passed through the coil *a*² to heat the liquid to the desired temperature. At the completion 35 of this operation the valves *c'* and *d*⁴ may be opened to permit the pressure within the digester to force the liquid through the pipes *c*, *d*, and *d*² to the exhaust, or by opening valves *c'* and *d*³ the liquid may be forced back 40 into the tank. The valves are then closed, and when it is desired to convey the solution from the digester *b* back to the digester *a* the 45 valves *c'* and *e*⁴ are opened to create a vacuum within the digester *a*, and then the valve *e*⁴ is closed and the valve *c*² opened to permit the solution to flow from digester *b* to digester *a*. At the completion of the operation 50 upon the material within the digester the cover thereof may be removed to permit the withdrawal of the material.

By the above construction the manual transfer of the flax or other material operated upon from one solution to another is obviated, and the solution itself is conveyed 55 from one position to another, and this transfer is accomplished by the pressures within the digesters, whereby the necessity of manual interference except for operating the valves is obviated. By this construction, furthermore, the material to be operated upon may be subjected successively to several liquids or solutions without removing the same 60 from the digester, so that the material after being placed in the digester remains therein until final completion. Thus the manual transfer of the material to be operated upon from one digester to another, as well as the 65 manual transfer of the solution, is avoided. The employment of two digesters, with means for transferring the solution from one to the

other, results in a great saving of labor and, furthermore, results in a saving of heat and energy, since the solution is transferred from one digester to the other while at a high temperature and without the necessity of cooling the liquid down, as would be necessary were the liquid to be drawn from the digester and subsequently returned to the same digester 70 and again heated. Furthermore, as the solution is subjected to pressure it may be passed from one digester to the other without excessive lowering of the pressure, thereby saving the energy which would otherwise be 75 required to raise the pressure to the required degree.

My invention may be applied to more than two digesters by duplicating the piping between the digesters. Instead of employing 85 the steam-pressure for moving the liquids compressed air or other fluid may be employed, being admitted to the digester by means of the valves *a*⁶ *b*⁶.

Having described my invention, what I 90 claim as new, and desire to secure by Letters Patent, is—

1. In combination, a pair of digesters or vats, a communication between the same, and means for maintaining a difference of gaseous 95 pressure between the interiors of said digesters to force the liquid from one digester to the other, substantially as described.

2. The combination with a pair of digesters or vats, of means for admitting liquid at will 100 to either digester, a heater for each of said digesters, a communication between the digesters, and means for forcing the liquid from either digester to the other, substantially as described.

3. The combination with a pair of digesters or vats, of removable covers therefor, a communication between the same, means for subjecting the interior of either digester to an excessive pressure at will and means for creating a vacuum in either of said digesters at will, substantially as described.

4. The combination with a pair of digesters or vats, of removable covers therefor, means for admitting liquid to either of the digesters 115 at will, a communication between the same, and means for creating a vacuum in either of said digesters at will to force the liquid from either of said digesters to the other, substantially as described.

5. In combination, a pair of digesters or vats, a communication between the same, and a heater for each of said digesters for producing a steam-pressure therein to force the liquid from one digester to the other, substantially as described.

6. The combination with a pair of digesters or vats, of removable sealing-covers therefor, a steam-heater for each of said digesters, a pipe extending between said digesters, a pipe 130 communicating with said digesters and leading to a vacuum-producer, a pipe communicating with the digesters and leading to a source of liquid-supply, and valves for con-

trolling the several pipes, substantially as described.

7. In combination, a pair of digesters or vats, a communication between the same, and steam-coils provided in each of said digesters for converting the liquid into steam in either digester to thereby create a pressure for forcing the liquid from one digester to the other, substantially as described.

10. 8. In combination, a pair of digesters or vats, a communication between the same, a steam-coil in each digester, a steam-supply pipe connected with both of said steam-coils and a pair of valves one for controlling the admission of steam to each steam-coil, substantially as described.

9. In combination, a pair of digesters or vats, a communicating pipe between the same, a steam-supply pipe and a vacuum-pipe connecting with said communicating pipe and valves for controlling the passage through said steam-supply and vacuum pipes, substantially as described.

10. In combination, a pair of digesters or vats, a communicating pipe between the same, a steam-supply pipe and a vacuum-pipe connected therewith, a steam-coil in each of said digesters connected with said steam-sup-

ply pipe, and valves for controlling the passages through said pipes, substantially as described.

11. In combination, a pair of digesters or vats, a communicating pipe between the same, and a steam-supply pipe, a vacuum-pipe, an exhaust-pipe, and a liquid-supply pipe, all connected with said communicating pipe, substantially as described.

12. The combination with a pair of digesters or vats, of removable covers therefor, means for admitting liquid from an outside supply to either of said digesters at will, a communication between said digesters, and means for continuously supplying and maintaining an excess of gaseous or steam pressure in the digester from which the liquid is to be withdrawn to thereby force the liquid from either digester to the other, substantially as described.

In witness whereof I have hereunto subscribed my name in the presence of two witnesses.
